(57) **CLAIM**

The ornamental design for a lamp, as shown and described.

DESCRIPTION

FIG. 1 is a front upper perspective view of a lamp of Applicant's design;

FIG. 2 is a front elevational view thereof;

FIG. 3 is a rear elevational view thereof;

FIG. 4 is a first side elevational view thereof;

FIG. 5 is a second side elevational view thereof, the second side elevational view being opposite the first side elevational view;

FIG. 6 is a top plan view thereof; and,

FIG. 7 is a bottom plan view thereof.

Where included, the broken lines show portions of the lamp and form no part of the claimed design.

The appearance of any portion of the lamp between the break lines forms no part of the claimed design.

1 Claim, 7 Drawing Sheets
